US0D1022734S

(12) **United States Design Patent** (10) **Patent No.:** **US D1,022,734 S**
(45) **Date of Patent:** **** Apr. 16, 2024**

(54) **DATA LOGGER**

(71) Applicant: **Willog Co., Ltd.**, Seoul (KR)

(72) Inventors: **Sung Hoon Bae**, Seoul (KR); **Ji Hyun Yun**, Pyeongtaek-si (KR)

(73) Assignee: **Willog Co., Ltd.**, Seoul (KR)

(**) Term: **15 Years**

(21) Appl. No.: **29/816,369**

(22) Filed: **Nov. 22, 2021**

(51) LOC (14) Cl. **10-04**

(52) U.S. Cl.

USPC **D10/78**

(57) **CLAIM**

The ornamental design for a data logger, as shown and described.

DESCRIPTION

FIG. 1 is a perspective view of a data logger showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIG. 3 depict portions of the data logger that form no part of the claimed design.

1 Claim, 6 Drawing Sheets
